(57) **CLAIM**

The ornamental design for a silicone basting spoon, as shown and described.

DESCRIPTION

FIG. 1 is a side perspective view of the silicone basting spoon.
FIG. 2 is a right side view of the silicone basting spoon.

FIG. 3 is a left side view of the silicone basting spoon.

FIG. 4 is a rear side view of the silicone basting spoon.

FIG. 5 is a bottom view of the silicone basting spoon.

FIG. 6 is a top view of the silicone basting spoon; and,

FIG. 7 is a front view of the silicone basting spoon.

The handle of the silicone basting spoon is for illustrative purposes only and forms no part illustrative of the claimed design. Only the head of the basting spoon is claimed.
